INTERCOM UNIT

Robert D. Kahn, Rockville Centre, N.Y., assignor to
Fedtro, Inc., Rockville Centre, N.Y., a corporation
of New York

Filed Apr. 28, 1967, Ser. No. 6,876

Term of patent 14 years

(Cl. D26—14)

FIG. 1

FIG. 2

FIG. 3

FIG. 4

FIG. 6

FIG. 5

FIG. 1 is a front elevational view of my new design for an intercom unit;

FIG. 2 is a left side elevational view thereof, the right side view being similar;

FIG. 3 is a top plan view thereof;

FIG. 4 is a rear elevational view thereof;

FIG. 5 is a bottom plan view thereof; and

FIG. 6 is a cross sectional view taken substantially along the line 6—6 of FIG. 1.

The dominant features of my design reside in the portions shown in full lines.

I claim:

The ornamental design for an intercom unit, substantially as shown and described.
